(57) **CLAIM**

The ornamental design for a metal clad dryer, as shown and described.

DESCRIPTION

FIG. 1 is a front perspective view of the present metal clad dryer;

FIG. 2 is a left side view of the metal clad dryer of FIG. 1;
FIG. 3 is a right side view of the metal clad dryer of FIG. 1;
FIG. 4 is a front view of the metal clad dryer of FIG. 1;
FIG. 5 is a rear view of the metal clad dryer of FIG. 1;
FIG. 6 is a top plan view of the metal clad dryer of FIG. 1;
FIG. 7 is a bottom plan view of the metal clad dryer of FIG. 1; and,

FIG. 8 is a rear perspective view of the present metal clad dryer.

The subject matter depicted in broken lines depicts portions of the present hair dryer not considered part of the claimed invention.
